Primary Examiner — Clare E Heflin(74) *Attorney, Agent, or Firm* — Saidman DesignLaw Group, LLC**CLAIM**

The ornamental design for a light, as shown and described.

DESCRIPTION

FIG. 1 is a perspective view of a light showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The drawings include surface shading which represents contour and not surface ornamentation.

The broken lines illustrate structure or features which form no part of the claimed design.

1 Claim, 8 Drawing Sheets(56)
